UNITED STATES PATENT OFFICE.

HOWARD I. BECKER, OF SCHENECTADY, NEW YORK, ASSIGNOR TO GENERAL ELECTRIC COMPANY, A CORPORATION OF NEW YORK.

AMPLIFIER.

Application filed December 14, 1921. Serial No. 522,378.

To all whom it may concern:

Be it known that I, HOWARD I. BECKER, a citizen of the United States, residing at Schenectady, county of Schenectady, State of New York, have invented certain new and useful Improvements in Amplifiers, of which the following is a specification.

My present invention relates to amplifiers of the electron discharge type, and more particularly to magnetically controlled amplifiers.

One of the objects of my invention is to provide a simple and efficient circuit connection of magnetically controlled amplifiers whereby a high degree of amplification may be obtained. A more specific object of my invention is to provide an amplifying system in which successive amplification of small currents may be produced in a single device.

The novel features which I believe to be characteristic of my invention are set forth with particularity in the appended claims. My invention, itself, however, both as to its organization and method of operation will best be understood by reference to the following description taken in connection with the accompanying drawing in which Figs. 1, 2 and 3 respectively show three different circuit organizations whereby my invention may be carried into effect.

I have indicated in each figure of the drawing two electron discharge amplifiers A and B, each of which comprises an evacuated receptacle 1, enclosing a filamentary cathode 2 adapted to be heated to incandescence by current from the battery 3, and a surrounding anode 4 which is preferably of cylindrical form arranged in substantially circular symmetry with respect to the cathode 2. A polarizing magnetic field for adjusting the normal current through these devices to a point where small variations in the magnetic field produce correspondingly large variations in the current between cathode and anode, may be provided by means of the coils 5 and 6, surrounding the receptacle 1, which are supplied with current from a convenient source such as the battery 7. Each of the devices is provided with an output circuit which includes a common source of potential 8 for maintaining the electron discharge between cathode 2 and anode 4.

The input circuit of amplifier A is sup-

plied with the current to be amplified, which in the cases illustrated is the current received upon the receiving antenna 9. A tuning condenser 10 is included in series with the antenna 9 and in shunt to the condenser 10 I provide a coil 11 which surrounds the receptacle 1. The output circuit of amplifier 8 includes a coil 12, which surrounds the receptacle 1 of amplifier B. The output circuit of amplifier A therefore serves as an input circuit for the amplifier B. The output circuit of amplifier B includes a coil 13, which is coupled to a coil 14, the coil 14 being included in a circuit which is tuned by means of variable condenser 15.

In the arrangement shown in Fig. 1 the tuned circuit which is associated with the output circuit of amplifier B includes a coupling coil 16 which is coupled by a variable coupling to the coil 17, which is in series with the input coil 11 of amplifier A. By means of this coupling amplified current variations produced in the output circuit of amplifier B are supplied to the input circuit of amplifier A and reamplified by both devices A and B. The tuned circuit which includes coils 14 and 16 and condenser 15 may also include a coil 18 which is coupled to a coil 19 from which the amplified currents may be supplied to other apparatus such as a detector or additional amplifiers. By adjustment of the coupling between coils 16, 17, it is possible to secure a very high degree of amplification without causing the production of oscillations.

I have also shown an arrangement whereby amplified currents may be supplied from the output circuit of amplifier A. This arrangement comprises a coil 20 which surrounds the receptacle 1 of amplifier B and is therefore in inductive relation to the coil 12. The circuit in which coil 20 is included also contains a variable condenser 21 for tuning purposes and the coupling coil 22 which is coupled to the coil 23. Amplified currents may be supplied if desired from the coil 23 to other apparatus such as a detector or additional amplifiers.

In some cases it may be desirable to supply to the input circuit of the first amplifier amplified potential variations produced in the output circuit of either amplifier A or amplifier B. In Fig. 2, I have shown an arrangement whereby this may be accom-

plished. In this case the circuit which includes the coil 20 also includes a coupling coil 24 which is coupled by a variable coupling to the coil 25, which is in series with the coil 11. In case the amplified variations to the output circuit of amplifier A are to be supplied to the input circuit of amplifier A the phase of such amplified variations will not correspond with the phase of the original variations impressed from the antenna 9 upon coil 11. This is due to the fact that an increase in the current in the input circuit of amplifier A produces a decrease in the current in the output circuit of said amplifier. It will be necessary therefore in this case to provide means for adjusting the phase of the variations supplied from the output circuit of amplifier A to the input circuit. Such phase adjustment may be provided by means of the variable condensers 26 and 27 and the inductance 28. In the arrangement shown in Fig. 2, means is also provided for supplying to the input circuit of amplifier A variations produced in the output circuit of amplifier B. This means comprises the coil 29 which is coupled by a variable coupling to the coil 28.

In Fig. 3 I have indicated an arrangement in which the variations produced in the output circuits of amplifiers A and B may be supplied by capacity coupling to the input circuit of amplifier A. In this case capacity couplings are provided between the coil 12 and coil 20 by means of condenser 30, and between coils 13 and 14 by means of condenser 31. The variable condensers 32 and 33 are inserted in the conductor 34, which is connected to one terminal of the coil 14 and one terminal of the input coil 11 of amplifier A. A switch 35 is also provided and when this switch 35 is closed variations produced in the output circuit of both amplifiers A and B will be supplied to the input circuit of amplifier A, and variations produced in the output circuit of amplifier B will be supplied through the capacity coupling furnished by condenser 32 to the input circuit of amplifier B. By proper adjustment of the condensers 32 and 33 the phase of the variations supplied from the output circuits of devices A and B to the input circuits may be given the proper relation.

While I have shown and described a preferred embodiment of my invention, it will be apparent that many modifications in the circuit connections employed may be made, and that as many devices as desired may be connected in series relation without departing from the scope of my invention as set forth in the appended claims.

What I claim as new and desire to secure by Letters Patent of the United States, is,—

1. The combination in an amplifying sys-

tem of a device having two electrodes arranged in substantially circular symmetry to each other, means for producing an electron discharge between said electrodes, an input circuit for said device which comprises means for magnetically controlling the discharge between said electrodes, an output circuit in which the current carried by the discharge will flow, a second device similar to the first, means associated with the output circuit of the first device for magnetically controlling the electron discharge in the second device, an output circuit for the second device, and means for impressing upon the input circuit of the first device current variations produced in the output circuit of the second device.

2. The combination in an amplifying system of a device having two electrodes arranged in substantially circular symmetry to each other, means for producing an electron discharge between said electrodes, an input circuit for said device which comprises means for magnetically controlling the discharge between said electrodes, an output circuit in which the current carried by the discharge will flow, a second device similar to the first, means associated with the output circuit of the first device for magnetically controlling the electron discharge in the second device, an output circuit for the second device, and means for impressing upon the input circuit of the first device current variations produced in the output circuit of one of said devices.

3. The combination in an amplifying system of a device having two electrodes arranged in substantially circular symmetry to each other, means for producing an electron discharge between said electrodes, an input circuit for said device which comprises means for magnetically controlling the discharge between said electrodes, an output circuit in which the current carried by the discharge will flow, a second device similar to the first, means associated with the output circuit of the first device for magnetically controlling the electron discharge in the second device, an output circuit for the second device, a common source of current for the output circuits of the two devices, and means for impressing upon the input circuit of the first device current variations produced in the output circuit of the second device.

4. The combination in an amplifying system of a device having two electrodes arranged in substantially circular symmetry to each other, means for producing an electron discharge between said electrodes, an input circuit for said device which comprises means for magnetically controlling the discharge between said electrodes, an output circuit in which the current carried by the discharge will flow, a second device similar to the first, means associated with the output

- circuit of the first device for magnetically controlling the electron discharge in the second device, an output circuit for the second device, means for impressing upon the input circuit of the first device current variations produced in the output circuit of the second device and means for adjusting the phase of the current variations impressed upon the input circuit of the first device.
- 5 5. The combination in an amplifying system of a device having two electrodes arranged in substantially circular symmetry to each other, means for producing an electron discharge between said electrodes, an input circuit for said device which comprises means for magnetically controlling the discharge between said electrodes, an output circuit in which the current carried by the discharge will flow, a second device similar 40 to the first, means associated with the output circuit of the first device for magnetically controlling the electron discharge in the second device, an output circuit for the second device, a common source of current for the output circuits of the two devices, means for 45 impressing upon the input circuit of the first device current variations produced in the output circuit of the second device, and means for adjusting the phase of the current variations impressed upon the input circuit 50 of the first device.
- 15 6. The combination in an amplifying system of a plurality of electron discharge devices, each of which has two electrodes arranged in substantially circular symmetry to each other, means for producing an electron discharge between the electrodes of each of said devices, input and output circuits for each of said devices, each of said input circuits comprising means for magnetically 55 controlling the discharge between the electrodes of the device with which it is associated, the output circuit of at least one of said devices having associated therewith means for controlling the input circuit of 60 another of said devices, said devices being connected in cascade for successive amplification, and means for impressing upon the input circuit of one of said devices amplified current variations produced in the output 65 circuit of a succeeding device.
- 20 7. The combination in an amplifying system of a device having two electrodes arranged in substantially circular symmetry to each other, means for producing an electron discharge between said electrodes, an input circuit for said device which comprises means for magnetically controlling the discharge between said electrodes, an output 70
- 25 30 35

In witness whereof, I have hereunto set my hand this 13th day of December, 1921.
HOWARD I. BECKER.
